UNITED STATES PATENT OFFICE.

HERBERT CHADWICK, OF BLACKBURN, ENGLAND, ASSIGNOR TO DRAPER COMPANY,
OF HOPEDALE, MASSACHUSETTS, A CORPORATION OF MAINE.

WEFT STOP-MOTION FOR WEFT-REPLENISHING LOOMS.

1,088,009.

Specification of Letters Patent. Patented Feb. 24, 1914.

Application filed November 5, 1912. Serial No. 729,635.

To all whom it may concern:

Be it known that I, HERBERT CHADWICK, a subject of King George V of Great Britain, residing at Blackburn, in the county of 5 Lancaster, England, have invented certain new and useful Improvements in Weft Stop-Motions for Weft-Replenishing Looms, of which the following is a specification.

This invention relates to automatic looms 10 of the feeler type wherein the running filling is replenished prior to complete exhaustion and a shuttle feeler is employed generally provided with a device to catch and cut the old or spent filling between the 15 cloth and the shuttle when filling replenishment is effected. In these looms it has been customary to locate the weft fork at the end of the loom opposite to that having the filling magazine or battery mounted 20 thereon, the means for catching the old thread on filling replenishment taking place, provided at the magazine end of the loom, causing the portion of thread extending from the thread catcher or holder to the selvage of the fabric or temple thread 25 cutter to assume such a position as to prevent the application of the weft fork at the same side of the loom as the filling hopper or battery.

It is advantageous to have the weft fork 30 operate at the magazine side of the loom, and the object of my invention is to provide means whereby the weft fork can be mounted between the edge of the fabric and 35 the shuttle box under or adjacent the filling magazine, and operate to detect weft absence and stop the loom without interfering with the usual operation of the shuttle feeler and thread catcher and parter, or being in the path of the weft thread extending 40 to such parter on weft replenishment taking place previous to being severed thereby and also the filling severed at the 45 selvage edge of the fabric by the temple thread cutter.

In order to lessen the parts on the loom I propose, in the preferred embodiment of 50 my invention, to stop the loom on weft failure by means of the warp stop motion, that is to say, I combine the weft fork motion with the warp stop motion so that detection of absence of weft by the weft fork 55 will act through the warp stop motion to stop the loom.

My invention will be described with ref-

erence to the accompanying drawing, in which:—

Figure 1 is a plan view of my improved weft fork arrangement; Fig. 2 is an elevation of the construction shown in Fig. 1 looking in the direction of the arrow A on 60 said figure, showing also the connection to the warp stop motion, Fig. 3 is an elevation showing some of the parts shown in Fig. 2, in different positions. Fig. 4 is a 65 side elevation of so much of a loom as is necessary to illustrate the invention.

Referring to the drawing, the weft fork 1 is, for the purposes of my invention, pivotally carried by a rod or bar 2 which is 70 fast to one end of a short spindle 3 mounted in bearings in a bracket 4 supported on the breast beam 5 at the magazine end of the loom, 5' representing a portion of the inner end of the magazine mounted in the 75 usual way on the breast beam. Fast on the opposite end of the spindle 3, is an arm or lever 6 having projecting therefrom a pin 7 which enters a slot 8 in a link 9 pivotally attached at one end to the usual 80 shuttle feeler 10. This shuttle feeler, as is well known, normally occupies an inoperative position, as shown in Figs. 1 and 2, but, on indication of substantial exhaustion of filling, is moved, by the rocking 85 of the usual rock shaft (not shown) by which the indications of the feeler are communicated to the transfer mechanism, into the position shown at Fig. 3, so that as the lay comes forward, it will be engaged by 90 the shuttle if the latter be improperly boxed and forced back, and through well known mechanism (not shown) prevent actuation of the transfer mechanism. As the shuttle feeler is moved into operative position, it 95 causes the arm or lever 6, through the link 9 to be raised. The raising of said arm or lever 6 through the spindle 3 causes the bar or rod 2 to be tilted upwardly at its rear end, to carry the weft fork up clear of the 100 portion of weft extending from the selvage of the fabric to the exhausted bobbin.

The shuttle feeler 10 usually has combined therewith means, comprising a fixed cutting blade 11 and a movable cutting 105 blade 12, the latter operated by an abutment on the lay, to cut the end of filling extending from the selvage of the fabric to the exhausted bobbin, a thread catcher 13 holding said end of filling, after it has been 110

severed by the actuation of the movable cutting blade 12 until it is cut at the selvage by the usual temple thread cutter.

The raising of the weft fork up clear of the end of filling, as above described, allows said filling to enter between the jaws of the cutting blades and to be placed in the thread catcher, which if the weft fork were allowed to remain in its operative position, as shown 10 at Fig. 1, would be prevented.

The shuttle feeler is moved to operative position before the lay comes to the front center and the link 9 causes the weft fork to be moved into its inoperative position 15 during the early part of such movement so that when the lay arrives at front center, the end of filling can pass without obstruction between the jaws of the cutting blades.

When the shuttle feeler moves back to inoperative position after filling replenishment has been effected, the weft fork is lowered again into operative position, but by reason of the positions of the pivotal center of the link 9 and of the pin 7, the weft fork 25 is not lowered until the end of filling has been carried back to such a position that when the weft fork descends the filling is behind the fork and is allowed to remain without interference until such time as it is 30 cut at the selvage by the temple thread cutter.

The tail end of the weft fork has a hook 14 as usual, which, according to the arrangement shown, is adapted to be engaged, when the lay beats up and the fork has not been 35 tilted by engagement with the filling, by the hooked upper end of a weft hammer lever 15 pivoted on a stud 16 carried by a suitable fixed part on the loom, the lower end of the said lever 15 being connected by a rod or 40 connection 17 and a lever arm 18 with the shaft 19 carrying the vibrator 20 of the usual warp stop motion.

The warp stop motion may be of the usual form, such for example as shown in the patent to Stone, No. 996,297, granted June 27, 1911. It comprises a series of detectors 21 through which the warp is threaded, said detectors being slotted longitudinally and supported on bars 22, 22, between fixed side plates 23, 23, carrying at their lower ends serrated plates 24, 24, in the usual way. The vibrator 20 is caused by the shaft 19, which is rocked by a cam or eccentric, to move to and fro beneath the plates 24, 24.

55 The cam or eccentric is shown at 25 in Fig. 4 of the drawing and through the usual mechanism including the links 27 and 28 rocks the vibrator 20. If a warp thread breaks its detector drops down into the path of the vibrator 20 and arrests the motion of the vibrator. Through the usual mechanism illustrated the hooked link 29 is then drawn upwardly rocking the knock-off lever 30 and throwing the shipper 31 to stop the loom. 65 Similarly therefore, if the hook 14 on the

weft fork 1 drops down and engages the hooked upper end of the lever 15, the latter cannot be moved by the lever arm 18 and connection 17 and the motion of the shaft 19 is arrested, thus causing the loom to be stopped in the same manner as if a warp thread had broken. Instead, however, of combining the weft fork motion with the warp stop motion in this manner, the usual weft stop mechanism may be employed.

In place of being controlled by the shuttle feeler as described the movement of the weft fork from operative to inoperative position at the time of weft replenishment may be effected by any suitable means connected with or controlled by the operation of the weft replenishing mechanism of the loom.

The details of construction and arrangement of the improvements may be varied without departing from the spirit and scope of the invention.

Having thus described my invention, what I claim as new and desire to secure by Letters Patent is:—

1. In a weft replenishing loom a weft fork and a thread catcher and parter all located at the magazine end of the loom and means to move the said weft fork, on filling replenishment being called for, to a position out of the path of the filling thread extending from the selvage of the fabric to the exhausted shuttle to enable said filling thread to be dealt with by the thread catcher and cutter. 90

2. In a weft replenishing loom a weft fork, a shuttle feeler, and a thread catching and parting means all located at the magazine end of the loom, and means operated by or through the shuttle feeler to move the said weft fork, on filling replenishment being called for, to a position out of the path 100 of the filling thread extending from the selvage of the fabric to the exhausted shuttle to enable said filling thread to be dealt with by the thread catching and parting means. 95

3. In a weft replenishing loom a weft fork, a pivoted support therefor, a shuttle feeler movable into and out of feeling position, a thread catching and parting means, all of the said elements being located at the magazine end of the loom, a link connecting the shuttle feeler and the said pivoted support whereby upon the movement of the shuttle feeler into feeling position the weft fork support will be swung on its pivot to move the said weft fork to a position out of the path of the filling thread extending from the selvage of the fabric to the exhausted shuttle to enable said filling thread to be dealt with by the thread catching and parting means. 110

4. In a weft replenishing loom the combination of a weft fork, a warp stop motion independent of the weft fork, and means whereby the weft fork, when in normal or operative position operates, on absence or 120 115 125 130

breakage of weft, to stop the loom through the medium of the warp stop motion.

5. In a weft replenishing loom the combination of a weft fork, a warp stop motion including a vibrating element, a weft hammer lever, a connection between said weft hammer lever and said vibrating element, whereby the absence or breakage of the filling causes the weft fork to lock the weft

hammer lever and thus actuates the warp stop motion to stop the loom.

In testimony whereof I affix my signature in the presence of two witnesses.

HERBERT CHADWICK.
